(57) **CLAIM**

The ornamental design for a load-mountable lifting eye, as shown and described.

DESCRIPTION

FIG. 1 is a top-front perspective view of a load-mountable lifting eye;

FIG. 2 is a front elevational view thereof, the rear elevational view being a mirror image thereof;

FIG. 3 is a left side elevational view thereof, the right side elevational view being a mirror image thereof;

FIG. 4 is a top plan view thereof;

FIG. 5 is a bottom plan view thereof;

FIG. 6 top-front perspective view of the swivel-mount embodiment thereof, wherein an optional mounting nut and retaining ring are illustrated in broken lines and do not form part of the claimed design;

FIG. 7 is a top-front perspective view thereof, wherein an optional mounting bolt, retaining ring and tightening tool are illustrated in broken lines and do not form part of the claimed design;

FIG. 8 is a cross-sectional view thereof taken along line 8-8 of FIG. 7;

FIG. 9 is a top-front perspective view of a second embodiment of a load-mountable lifting eye;

FIG. 10 is a front elevational view thereof, the rear elevational view being a mirror image thereof;

FIG. 11 is a left side elevational view thereof, the right side elevational view being a mirror image thereof;

FIG. 12 is a top plan view thereof; and,

FIG. 13 is a bottom plan view thereof.

The broken lines in the Figures represent environmental structure and form no part of the claimed design.
